C. H. FROELICH

LOCKING DEVICE FOR GUN TUBES

Filed Feb. 26, 1924

INVENTOR
Clarence H. Froelich.

BY

A. B. Reavis

ATTORNEY

UNITED STATES PATENT OFFICE.

CLARENCE HERVY FROELICH, OF BETHLEHEM, PENNSYLVANIA, ASSIGNOR TO BETHLEHEM STEEL COMPANY, A CORPORATION OF PENNSYLVANIA.

LOCKING DEVICE FOR GUN TUBES.

Application filed February 26, 1924. Serial No. 695,155.

To all whom it may concern:

Be it known that I, CLARENCE HERVY FROELICH, a citizen of the United States, and residing at Bethlehem, Northampton

County, State of Pennsylvania, have invented certain new and useful Improvements in Locking Devices for Gun Tubes, of which the following is a specification.

My invention relates to guns and it has for its object to provide simple and reliable locking means to hold a gun tube in place with respect to a movable recoil element.

In the application of Earl J. Miller, and myself, Serial No. 699,434, filed Mar. 15, 1924, and assigned to the Bethlehem Steel Company, there is disclosed and claimed a gun in which the tube has interlocking guide connections between a gun tube and stationary and movable recoil members. My invention has for its object more in particular to provide a mutilated screw type of connection to hold the tube in place with respect to the movable recoil member.

Apparatus made in accordance with my invention is illustrated in the accompanying drawings, forming a part of this application, in which

Figure 1 is a fragmentary view of a gun tube and recoil mechanism and showing portions thereof in section to more clearly illustrate my improved locking means;

Figure 2 is a view taken along the line II—II of Figure 1;

Figures 3, 4 and 5 are detail views of a locking screw;

Figure 6 is a rear elevation of the recoil mechanism; and,

Figure 7 is a detail view of a detent for the lever of the locking screw.

Referring now to the drawings more in particular for a better understanding of my invention, in Fig. 1, I show a gun tube 10 having its breech end 11 provided with a downwardly-facing joint member or portion 12, which is adapted to fit an upwardly-extending joint member 13 carried by the inner movable cylinder 14 of the recoil mechanism, at 15, as more particularly described in the application aforesaid.

The joint members 12 and 13 are provided with an interlocking guide connection extending longitudinally of the gun tube and of the movable recoil member, whereby the tube is removed and placed in position by longitudinal movement thereof with respect

to the movable recoil member 14. The lower joint member is provided at its rear end with an upwardly-extending abutment wall or projection 16 adapted to fit in a recess 17 in the upper joint member 12 and engage an abutment surface or shoulder 18 on the latter when the gun tube is in mounted position.

I provide a mutilated screw connection for holding the gun tube in place with respect to the movable recoil member. To this end, I show a shaft 20 having mutilated threads or ribs 21 and extending longitudinally of the movable recoil member and supported by bearings 22 and 23 so that said member extends above the top surface of the lower joint member 13 in order that it may fit into a recess 24 extending longitudinally of and in the lower face of the upper joint member 12. The recess 24 is provided with interior threads or ribs 25 to fit the mutilated threads or ribs 21. The space between adjacent ends of the threads or ribs 21 defines an angle not less than the angular extent of the threads or ribs 25 so that the shaft 20 may be turned to entirely disengage the threads or ribs in order that the upper joint member 12 and gun tube may be slid longitudinally with respect to the lower joint member 13 and movable recoil member. The forward bearing 22 is so shaped as to fit into the recess 24 and permit passage of the upper joint member thereover.

The shaft 20 is provided with a full threaded portion 26 at its rear end which engages the threaded bearing 23. This threaded connection provides for taking any thrust imposed on the shaft 20. Also, it provides for an easy mode of assembly of the shaft member 20, it being merely necessary to screw the mutilated portion through and thereafter screw the threaded portion 26 therein to the necessary extent.

The shaft 20 is turned by a lever 27 carried at its rear end, and I provide locking means for holding the lever in locking position. For the latter purpose I show a yieldable detent 28 carried by the lower joint member and adapted to snap into a recess 29 at the rear side of the lever, the forward side of the lever being beveled at 30 to facilitate passage thereof over the detent.

As illustrated, the detent 28 is held to the abutment wall by a nut 31 at the forward side of the latter. Accordingly, I show a recess 32 in the upper joint member in order

that the nut may not interfere with engagement of the abutment surfaces.

Having thus described the invention what I claim as new and desire to secure by Letters Patent is:

1. The combination with a gun tube member and a movable recoil member having an interlocking guide connection and cooperating thrust-transmitting abutments, of a row of teeth carried by one member, said row extending longitudinally with respect to the axis of the gun tube member, and a rotary element carried by the other member and having a row of teeth thereon for engagement and disengagement with the first teeth, said rotary element being rotatable about an axis which is parallel to the axis of the gun tube member and which is disposed eccentrically with respect to the latter axis.

2. The combination with a gun tube member and a movable recoil member having an interlocking guide connection and cooperating thrust-transmitting abutments, of a row of helically disposed teeth on one member, said row extending longitudinally with respect to the gun tube member, and a rotary element carried by the other member and having helically-disposed teeth thereon for engagement and disengagement with the first teeth by partial turns of said element, said rotary element being rotatable about an axis which is parallel to the axis of the gun tube member and which is disposed eccentrically with respect to the latter axis.

3. The combination with a gun tube member and a movable recoil member having an interlocking guide connection and cooperating thrust-transmitting abutments, of a recess in one member having interior threads and a rotary element carried by the other member and having threads for engagement and disengagement with the threads of the recess, said rotary element being disposed longitudinally with respect to the gun tube member.

4. The combination with a gun tube member and a movable recoil member having an interlocking guide connection and cooperating thrust-transmitting abutments, of a row of teeth carried by one member, said row extending longitudinally of the gun tube member, an element carried by the other member and rotatable about an axis extending longitudinally with respect to the axis of the gun tube member and having teeth thereon for engagement and disengagement with the first teeth for partial turns of said element, and means for locking the element in position with the teeth thereof engaged with the first teeth.

5. The combination with a gun member and a movable recoil member having an interlocking guide connection and cooperating thrust-transmitting abutments, of a longitudinal recess in one member having interior helical teeth, a shaft journalled on the other member and adapted to fit in the recess and having a row of helical teeth for engagement and disengagement with the first teeth.

6. The combination with a gun member and a movable recoil member having an interlocking guide connection and cooperating thrust-transmitting abutments, of a longitudinal recess at the breech end having interior helical teeth, a longitudinally-disposed shaft adapted to fit the recess, a journal bearing for the forward end of the shaft adapted to fit the recess, and helical teeth projecting from the shaft for engagement and disengagement with the first teeth by partial turns of said shaft.

7. The combination with a gun member and a movable recoil member having an interlocking guide connection and cooperating thrust-transmitting abutments, of a longitudinal recess carried by the gun tube and having interior helical threads, a shaft carried by the movable member and arranged to fit in the recess, mutilated threads carried by the shaft for engagement and disengagement with the threads of said recess, a bearing for the forward end of the shaft, a threaded bearing for supporting the rear portion of the shaft, and threads carried by the rear portion of said shaft for engagement with the threaded bearing.

8. In a gun, the combination with a gun tube and recoil mechanism, of cooperating joint members carried by the breech end of the gun tube and by the movable member of the recoil mechanism, an interlocking guide connection between the joint members and extending longitudinally of the tube and of the movable member, abutments carried by the joint members for limiting rearward movement of the gun tube with respect to the movable member, a threaded recess extending longitudinally of and in the face of one of the joint members, and a mutilated screw carried by the other joint member and arranged for engagement and disengagement with respect to the threads of said recess.

9. In a gun, the combination with a gun tube and recoil mechanism, of cooperating joint members carried by the breech end of the gun tube and by the movable member of the recoil mechanism, an interlocking guide connection between the joint members and extending longitudinally of the tube and of the movable member, abutments carried by the joint members for limiting rearward movement of the gun tube with respect to the movable member, a threaded recess extending longitudinally of and in the face of one of the joint members, and a mutilated screw carried by the other joint member and arranged for engagement and disengagement with respect to the threads of said recess, and locking means for holding the

screw in position with the threads thereof in engagement with the threads of the recess.

10. In a gun, the combination with a gun tube and recoil mechanism, of a downwardly-facing joint member carried by the breech end of the gun tube, an upwardly-extending cooperating joint member carried by the movable member of the recoil mechanism, an interlocking guide connection between the joint members and extending longitudinally of the gun tube and of the movable member, an abutment wall arranged at the rear end of the joint member of the movable element of the recoil mechanism, a shoulder carried by the gun tube joint member and adapted to contact with the abutment to limit rearward movement of the gun tube with respect to the movable element of the recoil mechanism and to transmit recoil stresses

between those parts, a threaded recess extending longitudinally of the gun tube joint member and arranged in the lower face of the latter, a shaft extending longitudinally of the joint member, mutilated threads carried by the shaft for engagement with the threads of said recess, a forward bearing carried by the movable recoil element joint member for the forward end of the shaft and adapted to fit freely within said recess, a 25 threaded bearing extending through the abutment, a threaded portion on said shaft for engagement with the threaded bearing, a lever for turning the shaft, and means for locking the lever in position with the interrupted threads of the shaft in engagement with the threads of the recess.

In testimony whereof I hereunto affix my signature this 31st day of January 1924.

CLARENCE HERVY FROELICH.
